WATCHMAN'S TOUR SYSTEM

Paul M. Farmer, West Orange, and Dwight W. Blosier, Teaneck, N. J., and William J. Kleinkecht, Norwalk, Conn., assignors to American District Telegraph Company, Jersey City, N. J., a corporation of New Jersey

Application September 18, 1943, Serial No. 502,918

30 Claims. (Cl. 177—360)

This invention relates generally to signaling systems, and more particularly to signaling systems used for the purpose of supervising the activities of watchmen where it is desired that each watchman complete a prescribed tour and report to a central station at the end of the tour. This application is a continuation in part of our copending application Serial No. 312,710, filed January 6, 1940, for "Watchman's tour system".

This system comprises a number of watchmen's tour stations situated in different parts of a building or other enclosure for the purpose of compelling a watchman to inspect given areas at prescribed times and within a certain overall time period. The tour station located at each end of the tour is adapted to transmit a supervisory signal to a central point, the station at one end usually indicating the start of a tour and the station at the other end indicating the finish of the tour. Each of the other stations on the tour contains a register operating member which conditions a register for operation by the next succeeding station only. Therefore, the watchman carries the register from station to station, and it is operated or conditioned at each station in such a manner that the watchman is compelled to visit the stations in a predetermined sequence, since any deviation from the prescribed tour, such as omissions of stations, or attempts to operate in a different sequence will prevent the watchman from properly actuating the register at any other station. If the watchman has operated his register in accordance with directions, he can transmit a supervisory signal at the final station, whereas failure to operate his register in the prescribed manner will prevent the register from causing transmission of the signal at the last station on the route. The transmitting stations are adapted to control a delinquency signal, and if they are not operated by the register within a prescribed period of time the central station operator is informed of a watchman's failure to start, or to properly cover, his route within the given time limit. Thus, it is not necessary that every station be capable of transmitting report signals.

Accordingly, the primary object of this invention is to provide an improved tour system which compels a watchman to cover a prescribed area on his tour.

A further object of this invention is to provide a tour system having a number of tour stations, each of which conceals the register and its op-

eration during the time that it is being operated at the tour boxes.

5 A further object of this invention is to provide a watchman's register and box which are self-operating to the extent that manipulation of the register by the watchman is reduced to the minimum.

10 Another object of the invention is to provide a register which cannot be tampered with in order to avoid the completion of a prescribed tour.

15 Still another object of this invention is to provide tour stations, both preliminary and transmitting, which are tamper proof.

20 Still another object of this invention is to provide a register which gives no indication of the changes occurring therein during the operation by the tour box.

25 A still further object of this invention is to provide a register which cannot be picked by the watchman to allow him to transmit a report signal without making the prescribed tour.

30 Further objects and advantages of this invention will be apparent from reading the attached specification taken in connection with the accompanying drawings, wherein:

Fig. 1 illustrates diagrammatically a system of watchman's tour stations;

35 Fig. 2 is an end view of a preliminary tour station;

Fig. 3 is a sectional view of a preliminary tour station showing the register drawer in open position and containing the register;

Fig. 4 is a sectional view of Fig. 3 taken on line 4—4;

35 Fig. 5 is a cross-section of a transmitting tour station with the register in its operated position and partially broken away to show the key;

Fig. 6 is a cross-section of Fig. 5 on line 6—6;

40 Fig. 7 is an enlarged plan view in cross-section of the register;

Fig. 8 is a section of Fig. 7 on line 8—8;

Fig. 9 is a section taken on line 9—9 of Fig. 7;

Fig. 10 is an end view of the register;

45 Fig. 11 is a section taken on line 11—11 of Fig. 7; and

Fig. 12 is a perspective of a portion of the key shown in Fig. 5.

The watchman's tour system includes, in accordance with this invention, a plurality of tour stations 1 to 10, shown in Fig. 1, for example, which are situated at different locations along the watchman's route whereby, as the watchman progresses along the route, his register, such as that shown in Figs. 3 and 7, is conditioned by

each station in a predetermined manner. The system may include any number of stations from 5 to 10, ten being shown for purposes of illustration only. It is necessary in systems of this type to compel the watchman to progress from one station to another, operating his register at the successive stations in predetermined order so that he is always forced to patrol a predetermined tour. At predetermined times, he inserts the register in station 1, thereby transmitting a report signal indicating that the tour is started on time. As the watchman proceeds, the register is operated by each of the stations in a progressive manner so that it is in condition at each successive station to be operated by that station only, and when he has completed his tour the register is in condition to operate the transmitting station which sends a supervisory signal over a transmission line to a central point where it is recorded or otherwise indicated by any suitable device 11. If the watchman fails to operate his register by visiting the tour stations in the prescribed sequence, or if he omits a tour station, the register will not be in condition to operate the transmitter, and since he is given a predetermined amount of time to complete the tour he will fail to transmit a supervisory signal before the expiration of that time, and the attendant will be informed of his failure by a delinquency signal.

Stations 2 to 9, shown in Fig. 1 of the drawings, are known as preliminary stations, and an example is shown in Figs. 2, 3 and 4 which will now be described in detail. The station includes an anchoring base 12 which is secured to a supporting wall by screws or any other suitable fastening means. Care is taken, however, to so fasten the base 12 to the wall and plate 13 to base 12 that special tools are necessary to remove the station box from the wall or to disassemble it.

A plate member 13 is supported on the base 12 and has a casing 15 attached thereto. The casing member encloses and supports a cylindrical drawer 16 having a top or cover 17 and a bottom portion for receiving the register 18 shown in Figs. 3, 5 and 7 to 11. The end of drawer 16 is provided with lugs 19 for engaging the key 20 on register 18 for positioning the same in operative relation to the keyhole 21, as shown in Figs. 3 and 4. When the register is inserted in the drawer, it is still possible to grasp the same and withdraw it, as the top of the drawer extends below the center line of the register, as shown in Figs. 2 and 3. The top or cover of the drawer has a lug portion 23 which meets the top of the casing at the point 24 when the drawer is opened. The upper rear portion of the drawer is provided with a rack 25 which engages with the pinion sector 26 on the lug 23 so that, when the drawer is almost entirely open, the cover is automatically opened. It should be noted that the cover of the drawer cannot be opened until the drawer is substantially completely withdrawn, thereby preventing the watchman from observing the characteristics of the key and the interior of the station. It is intended that any suitable means may be provided for opening the cover so long as it operates to keep the cover in closed position until the drawer is substantially open. Complete withdrawal of drawer 16 is prevented when the flanges on the bottom portions of the drawer 16 and casing 15 engage one another, as indicated in Fig. 3.

The member 13 supports a key 14 which is aligned in such a position that the register engages therewith when the drawer is returned to its closed position, the key 14 being so cut that it will unlock the register only if the predetermined previous station has been visited by the watchman. The spring 27 is provided for the purpose of maintaining the drawer in its closed position except when the watchman forcibly withdraws the same for the purpose of inserting his register.

The transmitting stations 1 to 10 are shown in detail in Fig. 5 and are similar to the preliminary stations except that the base member 13 supports transmitting contacts 22 and switching contacts 28 and 29. The key 14, shown in detail in Fig. 12, includes a fixed portion 30 which is attached to the base member 13, a shaft 31 rotatable within the key, a freely rotatable key portion 32 which is normally locked by the spring pressed ball 33, and an operating lug portion 34. The shaft 31 is secured to a contact operating member 35 whereby rotation of the lug 34 causes operation of the transmitting contacts 22, the purpose of which will be fully explained in connection with the operation of the register. Spring-pressed pin 38 normally abuts the end of contact spring 28 without exerting pressure on it. The pin 37 abuts spring 28 on the other side, and contact spring 29 normally holds sleeve 36 of insulating material in its outermost position. Contact springs 28 and 29 are adjusted so that they are normally open, making it necessary for sleeve 36 to be forced to the right against the pressure of spring 29 before closure of contacts 28 and 29 can occur. The reason for this arrangement will also be more fully described in connection with the register. The transmitting station or box is similar to the preliminary box in all respects except that the preliminary stations are not provided with contacts.

The register 18, shown in Figs. 7 to 11, includes an outer cylindrical casing 45 which has a lug 20 integral therewith and a hole 46 which exposes a station indicator ring 47 for the purpose of revealing the number of the previously operated station. It should be noted here that in contrast to prior registers the outer casing of this register does not present any indication of the manner in which the register operates, thus preventing the watchman from obtaining any clue as to the operating procedure which takes place within the register as he progresses from station to station. The other end of the cylinder is closed by an inner cylinder 48 which is pinned permanently to the casing 45 by the pins 50 so that it cannot be removed to expose the inner parts of the register. Furthermore, it is different from the usual cylinder lock in that the keyslot cannot change position when a key is inserted. These features of construction prevent the watchman from obtaining any hints as to how he might alter the register for the purpose of avoiding operation at the tour stations in order to transmit his report signal.

The lock portion of the register consists of the inner cylinder 48 which is provided with a key slot 49 and a set of pins for operating a plurality of sets of pins 51 in an intermediate cylinder 52 which lock the intermediate cylinder to the inner cylinder. A set of locking pins 51 is provided for each tour station, in this case ten stations, the sets being disposed in cylinder 52 as shown in Figs. 9 and 10. The lock portion of the register is arranged to require a different key for operat-

ing each set of pins 51. Thus, in the example shown, four pins are effective to lock the cylinder, but in the other stations, for example, a different combination of three or four pins may be effective to lock the cylinders. Thus, any desired combination of pins 51 may be utilized, with the result that each station has a different key and the watchman must visit the stations in predetermined sequence without omitting any station or stations. The pins 51 are designed to be loose fitting, while another pin 53 extending between cylinders 48 and 52 is designed to be close-fitting so that, if an attempt is made to pick the lock, it will not be possible to jam each of the pins 51 in position to unlock the cylinders. The inner cylinder 48 encloses a winding spring 61 for operating a driving member 55, which spring is wound by the winding member 63, this member being provided with ball bearings 64 which ride in helical slots 65, causing the spring winding member to rotate and wind the spring 61 as it is moved to the left. As an added precaution to prevent insertion of a pin of some sort to force a winding operation of the winding member, the pin 68 is provided so that the winding member 63 cannot move with respect to the inner cylinder 48 unless unlocked by the rotatable portion 32 of key 14.

The inner cylinder encloses the driving member 55 which rides on bearings 58 and carries a number of round rod-like pawls 56 on the ends of shoulders 60 secured to spring pressed pins 57. Due to the springs, the pawls are maintained in contact with ratchet teeth 59 (shown in dotted lines in Fig. 4) on the intermediate cross-axial face of cylinder 52. Such engagement prevents rotation of driving member 55 prior to movement of pins 53 to positions unlocking cylinder 52 for rotation relative to cylinder 48. Unlocking of pins 53 is accomplished by winding member 63 engaging and forcing pins 53' outwardly to the proper extent. Thus rotation of driving member 55 is prevented until the spring 61 has been wound by member 63 which not only winds spring 61 but also at the proper time clears pin 53 to unlock driving member 55, with the result that cylinder 52 is rotated under the impetus of spring 61.

As shown in Figs. 4 and 7, the ratchet 59 has ten teeth, one for each preliminary station, whereby the intermediate cylinder can be stepped through ten positions. If each position differs from adjacent positions either in number or disposition of pins 51, the intermediate cylinder will advance one station at a time, or through an arc of 36°, arrest of the intermediate cylinder at the end of the arc being accomplished by one or more of the pins 51 at the new position dropping into a pinhole or pinholes in the inner cylinder, in which hole or holes the pin or pins had not been elevated by the key. In the event the system is to be used with less than ten stations, for example, with nine stations, then a pair of adjacent positions will have similar pin numbers and dispositions to, in effect, eliminate one of the normal ten positions. If used with eight stations, then two pairs of adjacent positions will be so arranged. This elimination of stations, or compensation for a reduced number of stations, can be extended within limits. In any event, the greatest arc of movement of the intermediate cylinder under correct operating conditions is 72°, and any appreciable movement in excess of two positions is prevented by the provision of a stop 32 extending from the end of cylinder 48

into the path of movement of one of the shoulders 80. This stop is disposed at approximately 74° from a vertical line through the device, thereby preventing such excess movement as might possibly disrupt the operating mechanism.

The driving member 55 has a shaft 70 keyed thereto by key 85 and secured to winding member 63 by flange 72, there being a slot 73 in the end thereof for engaging the lug 34 on the transmitter shaft 31 to operate the transmitting station when the proper tour has been completed. Winding member 63 is provided with lug 84 for engaging with key 25 on shaft 70 for the purpose of causing rotation of shaft 70 and driving member 55 from the operated position back to normal position, as will be explained later on.

The pin 75 is provided in the inner cylinder 48 and abuts winding member 63 in slot 66 for the purpose of preventing tampering with the 20 register or the key and transmission of a false report signal. The pin 75 has another pin 76 perpendicular thereto which extends into a slot 77 formed by the space between the outer end of collar 78 on the intermediate cylinder 52 and the inner face of the end of cylinder 48, as shown in Figs. 7 and 10. Collar 78 while being of generally circular shape does not constitute a complete ring, there being a gap between the ends of the collar extending over an arc slightly in 30 excess of 36°, as shown in Fig. 10. Gap 77' is in communication with slot 77 and so situated that at stations 10 and 1 the pin 76 can move to the left into gap 77', thereby allowing the pin 75 to also move to the left as winding member 63 rotates. Thus, when the register is inserted in the drawer of the transmitting station, it allows the contact operating member 37 to remain stationary, while the sleeve 36 is displaced and closes contacts 28 and 29, as shown in Fig. 5. If, 40 however, the watchman plugs the aperture in the drawer or inserts any sort of instrument through the aperture in the drawer to operate the contacts 28 and 29, he will push both members 36 and 37, thereby displacing both contacts simultaneously in open relation to one another and preventing transmission of a report signal. Dummy pins 79 are permanently secured within the cylinder 48 by set screws, shown in Fig. 7 of the drawings, for the purpose of confusing the watchman. None of the pins including guard pin 75 can be moved when the watchman has the register, and therefore he cannot ascertain their function.

The ring 47, having station numbers thereon, 55 is supported by the flat springs 54 for the purpose of allowing movement of the ring in case the watchman attempts to change the station indication. Thus, he can insert a pencil or the like through aperture 46 and displace the ring 60 47, but upon withdrawal of his pencil the ring returns to the proper position, and in the meantime intermediate cylinder 52 is not moved or otherwise affected, as no appreciable force can be exerted thereon.

As the watchman progresses through his tour, he inserts the register in the drawer of each station, thus engaging the key with the register. He cannot perform any operation except the insertion of the register in the drawer and the return of the drawer to its normal position and, therefore, cannot force the operation of the register in any manner except the proper one. Furthermore, the register is completely concealed, and he cannot obtain any hint as to the operation taking place.

The key 14, in the case of a preliminary station, enters the key slot 49, and the rotating portion 32 of key 14 operates the pin 68 which unlocks the spring winding member 63. It is to be noted here that the conventional key blank cannot be utilized to operate the register because, even though a key blank could be found which would fit the slot 49, and even though it could be filed to operate the pins 51, it would not operate the winding member 63, as it would not have a rotating end portion. Further movement of the key causes rotation of the winding member 63 under the influence of the balls 64 and helical slots 65. The spring 61 is wound until the winding member 63 is forced toward the intermediate cylinder operating member 55. The locking pin 53 is released by winding member 63 while the pawls 56 engage the ratchet 59. It should be noted that the closely fitting pin 53 securely locks the inner cylinder 48 to the intermediate cylinder 52. Thus, even though a watchman succeeded in moving each of the pins 51, he could not jam these pins in their unlocking position, since they are loose fitting and pin 53 is tight fitting.

The cylinder 52 cannot rotate until all of the pins 51 and 53 are in position to unlock the two cylinders, and the driving member 55 cannot start its rotation until the pins are in the unlocking position. Therefore, the pins 51 and 53 are so positioned with respect to one another and the key for the winding member 63 that the key unlocks pins 51, the winding member 63 engages and moves pins 53', and consequently pins 53, so that the ratchet, engaged by the pawls 56, can rotate under the drive imparted by wound spring 61 at the instant that the two cylinders 48 and 52 become unlocked with respect to each other. Spring 61 in this manner rotates the intermediate cylinder 52 until a new set of pins 51 and 53 become aligned with the key slot on the inner cylinder 48. This new set of pins is made up of a different combination and corresponds to the next preliminary station. Thus, the register is prepared for operation by the next preliminary station and no other, as its key is the only one which will unlock the new combination of pins.

When the register is relocked and the drawer 16 is withdrawn by the watchman, the spring winding member 63 returns to its normal position under the influence of spring 61. As the winding member 63 returns to its normal position, the lug 84 on member 63, shown in Figs. 7 and 11, engages with the keyed portion 85 of shaft 70 to in turn rotate the driving member 55 back to its normal position in preparation for operation by the next tour station, the pawls riding over the sloping surfaces of the next teeth to finally be seated behind the shoulders of those next teeth.

The watchman progresses along the tour, resetting the register in each tour box by changing the setting of the intermediate cylinder, as described above. If he fails to visit one or more boxes or to operate the register at the boxes in the predetermined sequence, the key at the next box will not unlock the intermediate cylinder, and consequently the ring 47 always indicates the number of the last station to operate the register.

When the watchman inserts his register in transmitting stations 10 or 1, the winding member 63 and cylinder driving member 55 are operated in the same fashion as in a preliminary

box except that the keyed shaft 70 rotates the key shaft 31 through the connection established when lug 84, shown in Fig. 12, engages the slot 71 in shaft 70. Thus, when the register is reset, the contact operating member 35 closes the contacts 22 to transmit a report signal. The contacts 22, 28 and 29 are shown as normally open, but they may be normally closed and adapted to be opened by the members 35 and 37.

As an added precaution to prevent false operation of the register, the guard pin 75, shown in Figs. 5 and 7, must be in condition to move to the left in order to prevent the contact springs 28 and 29 from remaining open under the influence of the pin 37 and the cylindrical contact operating member 36. If the intermediate cylinder has been operated at the proper preliminary boxes, the slot 71 in collar 78 will be in the proper position to allow the pin 75 to move to the left, but the pin 75 extends backward sufficiently to engage the winding member 63, and thus the winding member must be forced to the left by the key 30 in the transmitting station before the pin 75 can move to the left. Thus, the watchman does not see a change in the appearance of the register, and furthermore he cannot discover that the pin has any function or what its function may be. He is also prevented from defeating the purpose of the pin itself as it is held in normal position by the winding member 63.

From the description set forth herein, it is evident that the register is so designed that its appearance does not change as a consequence of the operations which are performed on it during the tour. The lock cannot be operated by a conventional key, and it cannot be picked in view of the dimensions assigned to the pins 57 and 53. In addition, the watchman loses control of the register as he closes the drawer of the station box, and therefore he is prevented from forcing the register to accomplish any false operation thereof. In other words, the register is substantially self-operating.

The station boxes are so designed that, when the drawer is pulled to an open position, the cover remains closed and cannot be opened until substantially the open position is reached, and therefore the interior of the box including the key and the guard pins always remain concealed. Therefore, it is impossible for the watchman to obtain any hints as to the appearance of the key itself or of the remainder of the interior of the box. The drawer protects the register from any application of force while it is being operated by the key and also conceals the register to prevent the watchman from ascertaining the function of the pins 75 as well as the operations which occur within the register. The provision of a guard pin together with dummy guard pins prevents the watchman from learning the function of the guard pin, and the pins themselves provide an added safeguard against tampering with the register or with the station box equipment.

In other words, the watchman is required to visit every station on his tour, as failure to do so would cause a delinquency signal in the central station, and any tampering with the register or tour boxes cannot prevent a delinquency signal.

It is not intended that the invention shall be limited to any particular form of transmitter, as it will be plainly evident to any person having ordinary skill in the art that other transmitters

may be used, such as those adapted to transmit a code signal comprising a series of digits. Furthermore, it is not intended that this system shall be limited to any specific number of transmitting tour stations or preliminary tour stations, as the requirements of individual installations will determine the number of the various types of stations to be included within a specific system. It is further obvious that this invention can be adapted to any number of sets of locking pins and the required number of keys for operating them.

While the system has been described as having tours with transmitting stations at the ends of the tours and with preliminary stations therebetween, it will be evident to those skilled in the art that transmitting stations can be interspersed in the tour as may be desired and as conditions may require.

Various modifications of this invention and improvements thereof will occur to those skilled in the art, and therefore we desire that this invention shall not be limited except as required by the prior art and the scope of the appended claims.

We claim:

1. A watchman's tour station comprising a casing, a drawer therein adapted to be withdrawn from the casing for the purpose of receiving a watchman's register, means for limiting withdrawal of said drawer, the drawer including a cover having a lifting lug thereon for lifting said cover when the lug engages the front of the casing, an apertured wall for said drawer, a key mounted at the rear of the casing in fixed relation thereto and so aligned with the drawer aperture that it enters the register to operate the same when the drawer is pushed to its closed position.

2. In combination, a register and a watchman's tour station comprising a casing, means for introducing a register into said casing, a register operating means supported within said casing and means for rendering the operating means inaccessible prior to the introduction of a register into the casing and during the time a register is in the casing.

3. In combination, a register, a watchman's tour station for operating the register comprising a casing, a key supported at the rear of the casing in fixed relation thereto, a drawer for receiving the register and adapted to extend through the front of said casing, an aperture in the rear of said drawer and aligned with the key whereby the key extends into the drawer when the same is closed, said drawer having a cover thereon adapted to prevent observation of the interior of the station, said casing normally maintaining the cover in closed position, a lug at the rear of said drawer positioned to open the cover after it has been withdrawn from the casing to substantially the full open position whereby the key is concealed after the cover opens and the register is concealed when the casing forces the cover to closed position after the drawer is partially closed.

4. In combination, a register and a watchman's tour station comprising a casing, a register operating means supported within said casing and means for conveying the register into operating position with respect to the register operating means and for concealing the said register operating means and register during all operating functions.

5. In combination, a register, a watchman's

- tour station comprising a casing, a key supported at the rear of the casing in fixed relation thereto, a drawer for receiving the register and conveying it to an operative position with respect to the key, a cover on the drawer adapted to conceal the register and prevent access to the interior of the casing, said casing normally holding the cover in closed position, and means for opening the cover after the drawer has been withdrawn to substantially the full open position whereby the key is concealed when the drawer is open and the register is concealed after the drawer is partially closed.
6. A watchman's tour station comprising a casing, a drawer therein adapted to be withdrawn from the casing for the purpose of receiving a watchman's register, an aperture at the rear of the drawer, a cover on said drawer, means for opening said cover only when the drawer is substantially at the opened position, a key mounted at the rear of the casing in fixed relation thereto whereby it is concealed when the cover is open, the key being so aligned with the aperture of said drawer that it enters the register to operate the same when the cover is closed and the drawer is in its closed position.
7. In combination, a watchman's tour station comprising a signal transmitting means, a register operating key and means for operating the signal transmitting means and a register comprising a lock adapted to be operated by the key and means for resetting the lock and operating the second means to drive the transmitting means when the key has unlocked the register and the resetting operation occurs.
8. In combination, a watchman's tour station comprising a pair of transmitting contacts, a register operating key comprising a fixed station, a rotatable section and a shaft rotatable within both sections for operating the contacts, and a register comprising a lock adapted to be operated by the fixed section of the key, an operating device within the lock for unlocking the same and having a keyed member for engaging the contact operating shaft and a locked member which receives the rotatable section of the key and is unlocked thereby for rotating the operating device to rotate the shaft and operate the transmitter contacts when the key has unlocked the register and the relocking operation occurs.
9. In a watchman's tour station, a pair of transmitting contacts and a register operating key comprising a fixed section for unlocking the register, a rotatable section and a shaft rotatable within both sections for operating the contacts when engaged by the register.
10. In a watchman's register, an outer cylinder and an inner cylinder locked thereto and adapted to receive a key, an intermediate cylinder having loose fitting pins therein responsive to the key for locking the inner cylinder and the intermediate cylinder together in several different positions and an operating device for rotating the intermediate cylinder with respect to the inner cylinder comprising an operating member for rotating the intermediate cylinder, a close fitting pin for locking the intermediate cylinder to the inner cylinder and means responsive when the key becomes fully inserted for engaging the close fitting pin to unlock the cylinders and rotate the operating member whereby the inner cylinder and the intermediate cylinder do not become unlocked until the proper key is fully inserted and the intermediate cylinder cannot

be rotated to bind the key operated pins and unlock the cylinders.

11. In a watchman's register, a lock adapted to be successively operated from one locked setting to another, a key for unlocking one part of the lock, an operating device energized by the key for moving the lock to the next setting and means operated by the operating device for conditioning the lock for resetting whereby picking of the first key operated part of the lock does not permit resetting.

12. In a watchman's tour system, a tour station comprising a casing, a drawer within the casing for receiving a watchman's register, a key supported in proper relation with the register to enter and operate the same when the drawer is pushed to its closed position, a pair of contacts adapted to be closed by the key when the same is operated by the register for transmitting a signal, a second pair of contacts connected in series with the first mentioned contacts for completing the transmission circuit and an operating member for the second pair of contacts controlled by the register only to prevent transmission of a signal by tampering with the key.

13. In a watchman's tour system, a tour station comprising a casing, a drawer within the casing for receiving a watchman's register, a key supported in proper relation with the register to operate the same when the drawer is pushed to its closed position, a pair of contacts adapted to be closed by the key when the same is operated by the register for transmitting a signal, a second pair of contacts connected in series with the first mentioned contacts for completing the transmission circuit and an operating member for the second pair of contacts comprising a pin for engaging one contact, and a cylindrical operating member surrounding said pin for operating the other contact whereby either the cylindrical member may operate its contact or both the cylindrical member and the pin may move both contacts when the register is conveyed to operative position by the drawer.

14. In combination, a watchman's register comprising a cylinder having a pin therein extending to the outside thereof, means for locking said pin and a watchman's station comprising a key for operating the register and unlocking the pin after a predetermined number of register operations to allow the pin to recede within the cylinder, a pair of transmitting contacts adapted to be operated by said key, a second pair of contacts connected in series with the first pair of contacts for completing the transmission circuit, means engaging with the register for operating one of said second pair of contacts when the register is operated and means aligned with the pin in said register for operating the other of said second pair of contacts when the pin is locked whereby each of the second pair of contacts is moved simultaneously and remain open when the pin within the register is locked and the contacts are closed when the pin is unlocked.

15. In combination, a watchman's register comprising a lock having a plurality of pins therein extending to the outside thereof, means for locking said pins in such a position that they are flush with the end of the cylinder and a watchman's station comprising a key for operating the lock and unlocking one of the pins after a predetermined number of register operations to allow the pin to recede within the cylinder, a pair of transmitting contacts adapted

to be operated by said key, a second pair of contacts connected in series with the first pair of contacts for completing the transmission circuit, means controlled by the unlocked pin in said register and engaging the second pair of contacts whereby the second pair of contacts are held in open position if the pin within the register is locked and in closed position if the pin is unlocked.

16. In combination, a watchman's station comprising a pair of transmitting contacts for sending a supervisory signal, means for operating the transmitter contacts, a pair of auxiliary contacts in series with the transmitting contacts and a key associated with the contact operating means, a register adapted to be unlocked by the key and to operate the contact operating means when unlocked and auxiliary locked means in the register adapted to be unlocked by the key to operate the auxiliary contacts whereby tampering with the key does not cause transmission of supervisory signals.

17. In combination, a watchman's station comprising means for transmitting supervisory signals, a releasable guard device for preventing transmission of signals and a key associated with the transmitting means, a register adapted to be unlocked by the key and to operate the transmitting means when unlocked and auxiliary means in the register adapted to be unlocked by the key and cooperating with the guard device to prevent transmission of supervisory signals unless the register is properly preconditioned to release said guard device.

18. In a watchman's tour register, an outer cylinder and an inner cylinder locked thereto by a series of locking pins, an intermediate cylinder locked to said inner cylinder by a second series of pins, a key for unlocking the inner and intermediate cylinder, an operating device operated by the key for rotating the intermediate cylinder with respect to the inner cylinder through a series of locking positions, a series of locked pins extending through one end of the inner cylinder, only one of which has actual utility to control a pair of contacts, this pin having an operable locking member thereon abutting the operating device whereby the operable pin is imperceptible to the watchman, a collar on said intermediate cylinder having a slot therein which becomes aligned with the locking member after the intermediate cylinder has been unlocked and rotated a predetermined number of times whereby the locking member allows the operating pin to recede within the inner cylinder after the register has been operated through a predetermined sequence at a series of tour stations.

19. In a watchman's tour register, an outer casing and an inner cylinder locked thereto, an intermediate cylinder locked to said inner cylinder, a key for unlocking the cylinders, an operating device operated by the key for rotating the intermediate cylinder with respect to the inner cylinder through a series of locking positions, a guard pin extending through one end of the inner cylinder and means for retaining the guard pin in a locked position until after the intermediate cylinder has been unlocked a predetermined number of times whereby the guard pin is unlocked when the register has been operated through a predetermined sequence.

20. In a watchman's register, a casing, a lock device within the casing adapted to be rotated through a predetermined series of separate positions, a partially exposed ring flexibly attached

to the lock device by a series of flat springs for indicating its position, the springs allowing the ring to be rotated a slight amount if tampered with, but being adapted to return it to its normal position when the tampering ceases and preventing direct application of force to the lock.

21. In a watchman's register, a casing, a lock device within the casing adapted to be locked and unlocked a predetermined number of times, an indicator attached to the lock device by a resilient means for indicating the number of locking operations, the resilient means allowing the indicator to be moved a slight amount if tampered with, but being adapted to return it to its normal position when the tampering ceases and preventing direct application of force to the lock.

22. In a watchman's register, an outer cylinder and an inner cylinder locked thereto and adapted to receive a key, an intermediate cylinder having pins therein for locking it to said inner cylinder in several different positions and an operating device for rotating the intermediate cylinder with respect to the inner cylinder when a key is inserted in the register and unlocks the cylinders comprising an operating member having a set of pawls slideably mounted therein, a spring for rotating the operating member, a winding member mounted in spiral grooves on the cylinder and adapted to be forced through a winding motion by the unlocking key until the pawls are engaged and a ratchet on the intermediate cylinder engaged when the pawls slide under the influence of the winding member whereby insertion of the key winds the spring and the winding member engages the pawls with the ratchet to cause the spring to drive the intermediate cylinder to another locked position.

23. In a watchman's register, an outer casing and an inner cylinder locked thereto and adapted to receive a key, an intermediate cylinder having pins therein for locking it to said inner cylinder in several different positions and an operating device for rotating the intermediate cylinder with respect to the inner cylinder when a key is inserted in the register comprising an operating member and means driven by the key for storing energy, engaging the operating member with the intermediate cylinder and rotating the intermediate cylinder to a new locking position whereby only force stored by the storing means can be applied to the register when it is operated.

24. In a watchman's register, an outer casing and an inner cylinder locked thereto and adapted to receive a key, an intermediate cylinder having pins therein for locking it in several positions in a predetermined sequence to the inner cylinder, a series of keys for unlocking the intermediate cylinder in a predetermined sequence and means for storing a predetermined amount

of energy exerted when the proper keys are inserted and for driving the intermediate cylinder to successive locking positions whereby any amount of force applied to the exterior of the register cannot cause the intermediate cylinder to skip one or more positions.

25. In a watchman's register, an outer casing and a lock therein, a series of keys for unlocking said lock in a predetermined sequence and means for storing a predetermined amount of energy exerted when the proper keys are inserted to alter the lock and to prepare it for operation by the successive keys whereby any amount of force applied to the exterior of the register cannot alter the sequence of unlocking operations.

26. In a watchman's register, an outer casing, a lock therein for preventing improper operation of the register and means within said casing responsive to the key for operating the lock from one position to another position, said means having uniform energy expending characteristics independent of the energy of key motion, whereby application of force to the exterior of the register cannot operate the lock.

27. In a watchman's register, an outer casing and a lock therein, a key for unlocking said lock and means for storing a predetermined amount of the energy exerted when the proper key is inserted in said lock and means responsive to the storing means for relocking said lock.

28. In a watchman's register, an outer casing and a lock therein, said casing including a fixed key aperture, a key for unlocking said lock and means for storing a predetermined amount of the energy exerted when the key is inserted in the lock and means responsive to the storing means for relocking the lock whereby any amount of rotational or longitudinal force applied to the exterior of the register cannot cause relocking of the lock.

29. A watchman's tour station comprising a casing, a key supported therein, a drawer for receiving a register and conveying it to operable relation with respect to said key and a cover on said drawer engaged and closed by said casing when the drawer is inserted therein whereby insertion of the drawer automatically closes said cover.

30. In a watchman's register, a lock adapted to be successively operated from one locked setting to another, each setting requiring an individual key to unlock the lock, and an operating device within the register energized by each individual key for advancing said lock to the next setting thereof.
